UNITED STATES PATENT OFFICE.

SVAN NORDEN, OF CRANSTON, RHODE ISLAND, ASSIGNOR TO S. NORDEN & COMPANY, OF PROVIDENCE, RHODE ISLAND, A PARTNERSHIP CONSISTING OF SVAN NORDEN, OF CRANSTON, RHODE ISLAND, AND HERMAN S. RICH, OF PROVIDENCE, RHODE ISLAND.

ART OF FORMING AND AFFIXING TIPS TO CORSET AND SHOE LACES.

1,412,086.

Specification of Letters Patent. Patented Apr. 11, 1922.

Application filed July 31, 1919. Serial No. 314,449.

To all whom it may concern:

Be it known that I, SVAN NORDEN, a citizen of the United States, residing at Cranston, in the county of Providence, State of Rhode Island, have invented certain new and useful Improvements in the Art of forming and Affixing Tips to Corset and Shoe Laces, of which the following is a specification.

10 My invention relates to the art of affixing metal tips to corset- and shoe-laces and consists of improvements in the blank from which the tip is formed, and in the method of applying the same to the lace. One object 15 of my improvement is to provide as a new article of manufacture a novel form of metal blank that can be produced at a low cost and which may be applied to the lace by a simple method of rolling it therearound. 20 My improved method of applying the tip to the lace also effects a more secure joinder of the tip with the cord or braid, while also tending to cheapen the cost of manufacture, improve the finish and enhance the ornamental appearance of the completed article.

The manner and means for carrying out these improvements are fully described in the following specification, illustrated by 30 the accompanying drawings, in which like reference characters designate like parts.

In the drawings:

Fig. 1 is a perspective view showing one type of my improved tip-blank;

35 Fig. 2, a similar view showing the blank made in a slightly different shape;

Fig. 3, a view showing a slight modification in the form of the blank;

40 Fig. 4, a view showing the first mentioned type of blank applied to the end of the lace in the form of a tapered or pointed tip;

Fig. 5, a similar view showing the second type of blank applied to the lacing in the form of a straight tip;

45 Fig. 6, a plan view of the tip-forming dies which are employed with my improved method of rolling the tip-blank around the lace;

Fig. 7, an enlarged side elevation of the 50 same; and

Figs. 8 and 9, similar, enlarged views showing the dies in different coöoperative relation during their operation on the blank.

Tips for shoe- and corset-laces are usually

made from relatively thin sheet-metal and in my present improvement I provide a form of blank which may be stamped out and struck up in a punch-press by a single operation whereby to allow for its production in large quantities as an article of commerce which may be supplied to lacing manufacturers for general use in tipping the braids or cords fabricated in textile machines. As shown in Figs. 1 and 2, my improved tip-blank B consists in a flat strip of relatively thin sheet-metal having its marginal edges bent at right-angles to the plane of the main portion of the blank to form upstanding flanges or lips b—b. In Fig. 1 the body of the blank B is illustrated as being slightly tapered or wedge-shaped, with its opposite sides converging toward each other at one end. This form of blank B is designed to produce a conical or pointed tip T when rolled around the end of the lace as shown in Fig. 4; while the rectangularly shaped blank B' illustrated in Fig. 2 will form a straight tip T', see Fig. 5, when applied to the end of the lacing. It will also be noted from Figs. 1 and 2 that the blanks B—B' are punched with a series of small perforations which upsets the strip on its upper face to form sharp-edged projections b'—b'. These projections or prongs b'—b' are adapted to bite into the braid or cord when the blank B is clinched around the lace, whereby to grip its end and hold the tip from pulling off.

The bent over edges or lips b—b on the opposite marginal sides of the blank are designed to facilitate the operation of rolling the blank B around the end of the lace. For this purpose they coöperate with the rolling or bending dies in the manner as later explained. I have determined by experiment that one bent over edge suffices in most cases to attain the desired object, that is to say, the blank B' may be formed with one side-flange b² only as shown in Fig. 3; but for the sake of symmetry and to simplify the manufacturing operation in forming the blank the preferred type has both edges bent up at right-angles to the strip as illustrated in Figs. 1 and 2.

My improved process of rolling the tip-blank around the end of the lace and clinching it in place thereon is preferably performed in a set of coöperating dies such as

shown and described in detail in my U. S. Letters Patent No. 1,848,660, dated August 3, 1920. Referring to Figs. 6, 7, 8 and 9 of the present drawings, 2 designates the 5 base of the movable die D, and C is the opposite, fixed die which is cut away on its underside at 3 to allow the forward end of the die D to slide beneath it. The overhanging portion 4 of the fixed die C is undercut on its 10 forward end to form a beveled face 5 which is continued in a concaved recess 6 terminating in a sharp, prow-like edge 7 which merges into the upper surface of the base 2 of the die D. The base-plate 2 of the die 15 D is formed with an upstanding, curved ledge or shoulder 8 which is shaped to conform to the contour of the tip to be produced and which co-operates with the concaved recess 6 on the front of the fixed die C 20 in clinching the tip around the lace, see Fig. 9. Referring to Fig. 6, the top of the base-plate 2 is formed with a rectangular block or key-piece 10 adapted to serve as a holding-means and guide for the die D which slides 25 thereon. The die D is cut away at its center to form two opposite, parallel legs 11-11 which straddle the sides of the key-piece 10 and slide thereon. The die D is held in place on its base 2 by means of a flat plate 12 fastened to the top of the block or key-piece 10 30 and overhanging the sides thereof to bear against the legs 11-11 of the die. The top-plate 12 is fastened to the block 10 by means of dowel-pins 13-13 and a bolt 14 which 35 reaches down through the base-plate 2 to secure the latter to the support (not herein shown) on which the movable die is mounted. The bolt 14 is illustrated in section in Fig. 2, to render the drawing clearer, as is also the 40 bolt 15 which fastens the fixed die C to its support.

Extending across the recess between the legs 11-11 of the die D is a bow-shaped spring 16 which bears against the forward 45 end of the block 10 on the base-plate 2. The spring 16 tends to slide the die D forward on its base 2, and the movement of the die is limited by a stop-pin 17 projecting downwardly from the top-plate 12 into an enlarged hole 18 at the front of the die. The 50 forward end of the die D is beveled off on the top and undercut at the bottom to provide an overhanging, curved lip 19. The concaved under face of the lip 19 is formed 55 concentric with the upstanding, curved shoulder or ledge 8 on the base-plate 2 and registers therewith to form a half-circle when the die D is forced back into its retracted position as shown in Fig. 9. The 60 retraction of the die D is effected as its upper beveled face meets the correspondingly beveled under face 5 of the fixed die C when the two dies are carried together to clinch the tip around the lace. As this 65 action is completed the curved faces on

the dies come into register to form a complete circle. Normally, however, with the two dies separated to receive the blank B to be operated upon, the die D will be held by the spring 16 in its forward position with its 70 curved lip 19 advanced beyond the shoulder 8 on the base-plate 2. In this way the forward edge of the die D serves as an abutment or ledge 20, see Figs. 7 and 8, which overhangs the edge of the shoulder 8 on the plate 75 2 and clamps down the side of the blank B to hold it from lifting up out of position until the die D is withdrawn from over its edge. It will be noted from reference to Fig. 6 that the opposite undercut working-faces 19 and 6 of the dies D and C and the upstanding ledge 8 of the base-plate 2 are inclined slightly toward each other in a horizontal plane to adapt them to conform 80 to the tapered sides of the blank B, shown in Fig. 1, which is for pointed tips. When, however, a straight tip is to be applied to the lacing the working-faces of the dies are made parallel to adapt them to operate on the edges of the rectangular blank B' illustrated in Fig. 2.

Fastened to one side of the die D by means of a screw 24 is a vertical plate 25 which serves as a stop or limit for engaging the end of the blank B to locate it in position in setting it in place on the base-plate 2, between the working-faces of the dies. Extending forwardly from the top-plate 12 and reaching down across the beveled front face of the die D is a spring-arm 26 which is fastened in place by a screw 27. The forward end of the arm 27 is formed with fork-like tines or fingers 28 which are curled upwardly at their extremities. The fingers 28 are adapted to bear against the side of the 105 cord or lacing L as the movable die D slides toward the fixed die C to carry the cord over into position and hold it in place to be received within the edge of the blank B when the latter is rolled around it as shown in 110 Figs. 7 and 8. The tines or fingers 28 enter grooves 29 in the fixed die C as the die D moves toward the latter, the bottom of the grooves being inclined upwardly as shown by dotted lines in Fig. 6 to lift the spring-arm 27 out of the way as the working-faces of the dies come into register.

The method of operation of the dies in forming the tip and affixing it to the lacing is as follows: With the dies in open relation, as illustrated in Fig. 6, the blank B is laid flat on the top of the plate 2 with its end against the stop-plate 25. When the die D is in its fully retracted position the spring-arm 26 will be withdrawn sufficiently to 120 allow the blank to be conveniently set in place and the end of the lacing cord or braid L is then laid on top of the blank. The dies are operated in a suitable press or other machine and when the plate 2 is slid forward 125 130

beneath the overhanging portion 4 of the die C the die D will be carried with it with its lower projecting edge or abutment 20 overhanging the shoulder 8 on the plate. The 5 blank B carried on the plate 2 will thus be moved over against the working-face 6 of the die C and as it comes to rest the abutment 20 will slide across its rearward upturned lip b to clamp it down and hold it flat 10 as shown in Fig. 7. Meanwhile, the forward movement of the die D will also have carried the curved end of the spring-arm 26 against the side of the lacing L and the latter will have been pushed or slid over against 15 the underbeveled face 5 of the die C. Now, as the die D continues to advance it will push the blank B against the die C to roll its forward edge up around the lace L in the manner as illustrated in Fig. 8. This rolling 20 action is caused by the forward edge of the blank following the concaved face 5 on the die C as the side of the blank is pried or wedged away from the plate 2 by the sharp-edged prow 7. While the forward edge 25 of the blank B is thus being rolled around the lace L, the latter being maintained thereagainst by the spring-arm 26, the opposite rearward edge b is clamped down against the plate 2 by the overhanging 30 edge or abutment 20 on the die D. As the edge b of the blank being operated upon rolls or curls over the top of the lacing L the tines or fingers 28 at the end 35 of the spring-arm 26 slide into the grooves 29 in the die C, see Figs. 8 and 9, and are thereby lifted out of the way when the dies are finally brought together. As the die D comes into register with the die C the beveled face 5 on the latter engages the opposite inclined face on the die D to hold the latter from further movement while the plate 2 continues to move forward, this action being provided for by the yielding of the spring 16, see Fig. 6, as before explained. 40

45 As the die D is held in this manner the ledge 8 on the plate 2 slides out from under the overhanging edge 20 of the die to release the edge b of the blank B which has been held thereunder. It will be understood that the 50 sliding movement of the die D on the plate 2 is limited by the engagement of the pin 17 with the sides of the hole 18, see Fig. 6. This provides that when the concaved edge 19 of the die D comes into concentric register 55 with the curved face of the ledge 8 on the plate 2 the die will be held fast with the plate. Therefore, as the plate 2 reaches the end of its stroke, with its end engaging the shoulder 3 on the die C, the two working- 60 faces of the dies D and C will be pressed firmly against the sides of the blank B to clinch its overlapping edges together as shown in Fig. 9. This final clinching action of the dies causes the prongs b' on the inner 65 surface of the blank B to bite into the sides of the lacing L, while also tending to set the blank to prevent its edges from springing apart. In this way the blank B is caused to be constricted snugly around the lacing while compressing the latter slightly, as 70 shown in Fig. 9, so that when the tip is removed from the dies it will have a smooth, practically unbroken joint where its end overlaps the lace and will present an extremely neat and finished joinder therewith 75 while being held firmly and securely in place thereon.

The conical or pointed form of tip T shown in Fig. 4 is usually applied to round laces, so-called, but with flat, tubular laces 80 a straight tip is employed. The straight type of tip T' is illustrated in Fig. 5 and is affixed to the lace in substantially the same manner as above explained in reference to the conical tip. For a straight tip the blank 85 is made rectangular with its marginal edges parallel as shown in Fig. 2, and the dies C and D have parallel working-faces as before explained. During the process of rolling this form of tip around the lace the end of 90 the latter is doubled on itself or folded together, as indicated in Fig. 9, where the side of the blank curls around it. As here shown the edge b of the blank curls into the folded seam 1 of the fabric and takes a firm grip 95 thereagainst, while the opposite edge of the blank is clinched around it. In this way the edge of the blank is caused to take a firm bite on the lace L to secure the tip against pulling off and the finished tip T' will have a 100 closer fitting and neater appearance.

It will be seen from the foregoing that my improvement provides a partly formed blank which may be produced in large quantities at low cost to serve as an article of commerce in the nature of a "finding" or supply part for corset- and shoe-lace manufacturers. Moreover, my novel form of blank may be more easily and conveniently applied to the lace by the improved method 105 of manipulating it in the dies as herein set forth, and when formed into the tip it gives a more secure fastening with the end of the lace and presents a neater and smoother appearance in the finished article. 110

What I claim for my invention and desire to secure by U. S. Letters Patent is:—

1. An improved method of forming tips and affixing the same to corset- and shoe-laces consisting in first bending a substantially flat strip of sheet-metal along its side to provide a right-angled longitudinal flange; holding the under side of the strip flat against a rest by clamping down one of its marginal edges; and prying up the opposite bent edge of the strip to roll it around the end of the lace. 120

2. An improved method of forming tips and affixing the same to corset- and shoe-laces consisting in forming a blank from a strip 130

of flat sheet-metal having its longitudinal edges bent at right-angles to the plane of the strip; holding the under side of the blank flat against a rest by clamping down one of its edges; and applying pressure on the opposite edge of the blank to roll it around the lace and clinch it in place thereon.

3. An improved method of forming tips and affixing the same to corset- and shoe-laces consisting in bending up a blank from a flat strip of sheet-metal to form a narrow right-angled flange extending along its side; holding the under side of the blank flat against a rest by clamping down one of its marginal edges; applying the end of the lace to the top of the blank and holding it thereagainst; and exerting pressure beneath the bent up side of the blank to roll it around the lace.

4. An improved method of forming tips and affixing the same to corset- and shoe-laces consisting in bending up a blank from sheet-metal to form a trough-like strip having opposite right-angled flanges extending

along its sides; holding the under side of the strip flat on a rest by pressure against one of its upturned edges; applying pressure beneath the opposite upturned edge of the blank to roll it around the lace; and finally clinching the rolled over sides of the blank together at their joinder.

5. An improved method of forming tips for corset- and shoe-laces and applying the same thereto consisting in bending up a blank from sheet-metal to form a trough-like strip having right-angled flanges extending along its sides; holding the under side of the blank flat on a rest by pressure against one of its upturned edges; applying a prying pressure beneath its opposite side to roll the blank around the lace; and finally removing the downward pressure on the edge of the blank while clinching its sides together around the lace.

In testimony whereof I affix my signature.

SVAN NORDEN.
